CLAIM

The ornamental design for a lid, as shown and described herein.

DESCRIPTION

FIG. 1 is a top perspective view of a lid, showing our new design;

FIG. 2 is a bottom perspective view thereof;

FIG. 3 is a front view thereof;

FIG. 4 is a back view thereof;

FIG. 5 is a left side view thereof;

FIG. 6 is a right side view thereof;

FIG. 7 is a top plan view thereof; and,

FIG. 8 is a bottom plan view thereof.

The broken lines in the figures illustrate portions of the lid that form no part of the claimed design.
